AUTHUR W. CAPS, OF ROCHESTER, NEW YORK, ASSIGNOR TO PHOTOSTAT CORPORATION, OF PROVIDENCE, RHODE ISLAND, A CORPORATION OF RHODE ISLAND

PHOTOGRAPHIC-PRINT-TREATING APPARATUS

Application filed March 1, 1929. Serial No. 343,655.

The present invention relates to photography and more particularly to the treatment of photographic prints after they have been exposed in a camera. The invention is especially applicable to so-called "commercial cameras" in which exposures are made on successive portions of a roll of sensitized sheet material, the exposed portions then being severed from the roll and treated by suitable print treating apparatus including developing and fixing baths.

It is particularly with the print treating baths that the present invention deals, and preferably with the fixing bath, although it is also applicable to the developing bath or to other baths such as washing baths. An object of the invention is the provision of means for moving the bath container in a novel way in order to produce efficiently waves in the bath which will flow over and submerge a print placed therein.

Another object of the invention is the provision of means for twisting or shifting a print while it is being removed from print conveying mechanism, in order to assist such removal. Preferably this twisting of the print is caused by the same movement of the container above mentioned, which creates the waves in the bath.

A further object is the provision of stationary guiding means in a movable bath container for limiting the movement of a print within the bath when the container is moved, and the provision of improved driving mechanism for the parts.

To these and other ends the invention resides in certain improvements and combinations of parts, all as will be hereinafter more fully described, the novel features being pointed out in the claims at the end of the specification.

In the drawings:

Fig. 1 is a side elevation of a portion of a commercial camera showing a preferred embodiment of the invention applied thereto, and illustrating particularly the driving mechanism;

Fig. 2 is a vertical section taken longitudinally through the apparatus slightly inside the right hand wall of the casing;

Fig. 3 is a horizontal section substantially on the line 3—3 of Fig. 2, illustrating portions of the drive for the print removing means;

Fig. 4 is a fragmentary vertical section through the forward end of the print treating bath and associated parts, taken substantially along the center line of the apparatus;

Fig. 5 is a fragmentary plan illustrating details of the print conveying mechanism;

Fig. 6 is a transverse vertical section through the apparatus showing the bath container in one position;

Fig. 7 is a similar view showing the bath container in another position, and

Fig. 8 is a fragmentary plan of the bath container, parts of the casing being shown in horizontal section.

Similar reference numerals throughout the several views indicate the same parts.

The drawings illustrate, especially in Figs. 1 and 6, a pair of horizontal frame members 10 from which is hung a casing comprising side walls 11. A portion 12 of the casing projects upwardly above the frame members 10 at the forward end of the walls 11 and constitutes part of the exposure chamber of a camera, the other parts of which are not shown. Within this exposure chamber there is suitable means, not shown, for holding sensitized sheet material in position to be exposed, and for feeding and severing the exposed portions of the sheet material, as will be understood by those familiar with commercial cameras.

The severed prints are picked up by suitable print conveying mechanism which may include, for example, a pair of endless members such as the chains 15 guided over suitable sprockets 16, 17, 18, 19 and 20 so that these chains have a predetermined path of travel along an endless circuit. The chains are provided with suitable means for picking up and carrying along the exposed prints, which means may comprise a plurality of spaced pin bars 21, as shown in Fig. 5, each pin bar being secured at one end to the right hand chain and at the other end to the left hand chain, so that each pin bar extends transversely across the apparatus.

within the casing, and travels along when the chains are moved. Pins 22 are fixed to each pin bar 21 and project forwardly therefrom in the direction of travel of the conveying mechanism. An exposed print is impaled upon these pins in a manner understood by those skilled in the art, and is thus drawn along when the conveying mechanism is moved. Preferably the path of travel of the conveying mechanism passes through a developing bath and through one or more washing baths (not shown) so that the print is developed and washed during its travel.

In the embodiment of apparatus here illustrated, the conveying mechanism then moves vertically upwardly near the back of the apparatus or near the left hand end of Fig. 2, passes over the sprocket 16, the print meanwhile being guided by the roller 25, and thence moves forwardly substantially horizontally over a container 26 which holds a print fixing bath such as hypo or the like.

During the travel of the conveying mechanism over the container 26, the forward edge of the print is impaled upon the pins 22 while the rest of the print trails along behind, the free portion of the print back of the impaled forward edge falling by gravity into the bath within the container 26 as the conveyor moves.

As the pin bar 21 on which the print is impaled nears the forward end of the container 26, the print is removed therefrom so that the entire print falls into the container. To accomplish this removal readily, the sprockets 17 and 18 are arranged so as to cause the conveyor to reverse its direction of movement so that the pins 22 will for a moment be projected rearwardly in the manner illustrated in Fig. 4. When the parts are in this relationship, the print illustrated at P in this figure, is removed from the pins by the wiping action of an oscillating wiping member having resilient fingers 30 of rubber or the like fixed to a plate 31 mounted on an oscillating shaft 32, mechanism hereafter described being provided for causing this oscillation. As the fingers 30 oscillate rearwardly, they come into contact with the upper edge of the print P projecting slightly above the pin bar 21, as will be clearly apparent from Fig. 4, and wipe this print rearwardly off of the pins so that it is entirely freed from the conveying mechanism and falls to the fixing bath within the container 26. The conveying mechanism may then move on without the print and the pin bar may pick up another exposed print and convey it through the developing bath and to the fixing bath, in the same manner.

It sometimes happens that a print sticks slightly on the pins 22 on which it is impaled, so that the wiping movement of the fingers 30 does not effectively remove the print from all of the pins. Also it frequent-

ly happens that when a print is freed from the conveying mechanism and falls into the container 26, it remains floating for a considerable time on the surface of the bath unless means is provided for submerging it. The submergence of the print in order to obtain thorough and uniform action of the bath thereon is especially important where, as in the present instance, the print is deposited in the bath with its sensitized or emulsion side uppermost.

According to the present invention, novel means is provided which not only assists the removal of the prints from the conveying means but also insures the effective submergence of each print so that it will be acted upon thoroughly and uniformly by the fixing solution. This novel means preferably comprises means for moving the bath container 26 in a lateral or transverse direction, which movement produces a twisting action on the print impaled on the pins 22 and thus assists the removal of the print from the conveying mechanism, and which also produces waves in the bath which flow over the print effectively and submerge it quickly, so that it will be acted upon properly and uniformly by the treating bath. A lateral movement of the bath container is more advantageous than a longitudinal movement not only because it twists the print and helps to remove it from the conveying mechanism, but also because the container ordinarily has considerably less breadth than length, and waves need not be so high or of such great amplitude to flow entirely across the container as would be required to flow the length of the container. Hence the container need not be reciprocated so violently in a transverse direction as in a longitudinal direction, less power is required, and the submerging action of the waves is more rapid and reliable.

In order to permit this lateral movement of the container, it is mounted upon a pair of rollers 40 rotatably journaled in bearings 41 supported on a horizontal plate 42 extending across the apparatus. These rollers 40 extend longitudinally of the apparatus, so that the container supported on them may move transversely. Since the container 26 is preferably made of hard rubber or the like, a metal shell 43 is provided extending across the bottom and partially up the sides of the container, this shell providing a smooth bearing surface for rolling on the rollers 40, and preventing wear of the container itself.

Each of the rollers is provided with a groove 44 extending circumferentially around the roller, and a strip 45 fixed to the bottom of the member 43 runs in these grooves 44 and acts as a guiding rail preventing any twisting of the container and insuring true parallel motion thereof.

The movements of the container are preferably produced by the same driving means

which oscillates the print removing means and the print conveying mechanism. Such driving means, as illustrated in Fig. 1 comprises for example a motor 50 arranged, through suitable gearing within the gear box 51, to drive continuously a vertical shaft having a bevel gear 52 at its upper end. This bevel gear meshes with another bevel gear 53 on the forward end of a horizontal shaft 54 which carries another bevel gear 55 at its rear end, and which also has a spiral gear 56 near its rear end.

The bevel gear 55 drives another bevel gear 57 on a short vertical shaft 58 provided with a crank member 59 at its upper end, this crank member having a crank pin 60 which, as shown in Figs. 7 and 8, is connected by a link 61 to a bracket member 62 fixed to the shell 43 of the container 26. Thus, the continuous rotation of the shaft 54 produced by the motor 50 rotates the crank pin 60 and reciprocates the bath container in a transverse direction. This reciprocation produces waves in the bath which flow over and submerge the print, and it also moves the rear end of the print transversely to some extent, thus twisting it and assisting its removal from the pins 22.

The print removing means is driven from the spiral gear 56 above mentioned. This spiral gear meshes with another spiral gear 65 to which is fixed a crank 66 connected to one end of a link 67. The other end of this link is pivoted to an arm 68 at the outer end of a short rock shaft 69 which extends through the side wall 11 of the casing and which carries another arm 70 at its inner end. This inner arm 70 of the rock shaft is connected by a link 71 to arm 72 on the shaft 32 which supports the wiping fingers 30 of the print removing means. Thus, the rotation of the shaft 54 not only reciprocates the bath container 26, but also oscillates the print removing means.

It will be noted especially from Fig. 3 that the link 71 which connects the arm 70 to the arm 72 is of U-shaped form. This is necessitated by the fact that the arm must extend around a depending lug 73 on which the sprockets 17 and 18 are mounted, and accordingly this U-shaped construction is adopted. The link must extend around the outer side of this lug 73, since if it extended directly from the arm 70 to the arm 72 it would be in the path of travel of pin bars 21.

The endless members 15 of the conveying mechanism may be driven continuously but are preferably driven intermittently by suitable gearing of known construction within the gear box 51. The driving is arranged to be started by depression of an operating plunger 75, which may be moved by a handle 76 shown in Fig. 1. When the driving of the conveying mechanism has once been started by operation of the handle 76, it will continue

until the mechanism has been driven a predetermined distance, and then the driving will automatically cease until the plunger 75 is again depressed. The shaft 54 is preferably driven continuously, however, so that the bath container is constantly reciprocated to cause waves in the liquid therein even when the conveying mechanism is at rest.

The present invention also provides guiding means within the print treating bath for limiting somewhat the movements of the prints in response to the reciprocating movements of the bath container. This guiding means may comprise a grid-like structure formed of a series of wires bent to the shape best shown in Figs. 6 and 7. Each wire has a straight portion 80 extending transversely across the bath container slightly above the bottom thereof and below the surface of the liquid bath, side portions 81 extending upwardly from the ends of the portion 80, and terminal portions 82 fixed at their outer ends to inwardly extending ledges or flanges 83 which are secured to the side walls 11 of the casing. Thus this grid-like structure remains stationary when the bath container reciprocates, and it acts as a means for limiting somewhat the movements of the prints within the bath, although the guiding means is somewhat wider than the width of a print so that limited movement of the print is permitted.

Fig. 7 illustrates the bath container at the extreme right hand end of its reciprocation, and shows that the left hand side portions 81 of the grid wires are so placed that they will be slightly spaced from the left side of the container when it is in this position. Similarly, when the container reaches the extreme left hand end of its reciprocation, the right hand side portions 81 of the grid wires will be slightly spaced from the right side of the container. Thus the prints within the grid-like structure are prevented from coming into contact with the side walls of the bath container during the reciprocations thereof, so that they cannot stick to the sides or prevent the proper formation of waves by the reciprocating movement.

The inwardly extending flanges 90 at the upper edge of the container 26 prevent to a large extent the splashing or spattering of the liquid within the container when the container is reciprocated. Some slight spattering might occur, however, and in order to prevent such spattering from reaching undeveloped prints waiting to be picked up near the forward end of the apparatus, guard members are provided as shown in Fig. 4. These guard members include a vertical plate 91 extending across the casing from one side wall 11 to the other, and another vertical plate 92 likewise extending across the casing and overlapping the upturned end 93 of the plate 42 on which the rollers 40 are supported.

Any liquid which splashes or spatters out of the container 26 will thus be prevented from reaching a point where it might do damage, and will be directed onto the plate 42, from which it will be drained through the slot 95 (Fig. 2) through which the drain pipe 96 of the bath container 26 extends.

In operation, an exposed print is picked up by the conveying mechanism by being impaled on the pins 22, and is brought along through developing and washing baths and up over the roller 25 (Fig. 2) to the fixing bath within the container 26. As the pin bar carrying the print moves forwardly above this container, the forward edge of the print will be held up by being impaled on the pins while the rest of the print will trail along in the bath, as is illustrated in Fig. 4. When the pin bar 21 to which the print is attached passes around the sprocket 17 and thus reverses its direction, the rearward movement of the oscillating fingers 30 will wipe the impaled forward edge of the print off of the pins 22 so that the print is freed and the forward edge thereof falls to the surface of the bath on which the rest of the print is already lying.

During this time, the container 26 is constantly being reciprocated in a transverse direction and this motion is transmitted to some extent to the rear end of the print which is in the bath. Accordingly, since the rear end is shifted back and forth in a transverse direction while the front end is held against transverse movement by the pins 22, the print is somewhat twisted back and forth and this greatly assists the removal of the print from the pins 22.

When the print has been freed from the pins and is floating upon the surface of the bath, it is quickly submerged in the bath and thoroughly acted upon, by means of the waves which are formed on account of the reciprocations of the bath container. The reciprocating movement of the container in a transverse direction rather than in a longitudinal direction is particularly advantageous not only because it produces the above mentioned twisting action on the print, but also because the waves produced in the bath are more efficient and effective than when the container is moved longitudinally. Since the container has considerably less breadth than length, transverse waves do not have to flow as great a distance in order to flow completely over the print as longitudinal waves would have to do. Thus transverse waves of lesser height or amplitude will act as effectively upon the print as longitudinal waves of considerably greater height or amplitude. The wave action stirs up the liquid in the bath and keeps it of uniform consistency.

The grid-like structure prevents the print from coming into contact with the sides of the bath container 26 during the reciproca-

tions of the container, and thus the print is kept from sticking to the sides and from interfering with the formation and proper flow of the waves.

From the foregoing description it will be seen that an improved apparatus has been provided in which the photographic prints are easily removed from the conveying mechanism and in which they are quickly submerged in a print treating bath so that they are thoroughly acted upon by the bath. The apparatus is comparatively simple, requires only a small amount of power to operate it, and is of rugged and durable construction.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. In a photographic apparatus, the combination with a container for holding a photographic print treating bath, said container having a greater dimension in a longitudinal direction than in a transverse direction, of a plurality of rollers for supporting said container, said rollers having their axes extending longitudinally of the container, and mechanism for shifting said container in a transverse direction to create waves in the bath to flow over and submerge a print deposited in the bath.

2. In a photographic apparatus, the combination with a container for holding a print treating bath, of a plurality of rollers for supporting said container, a groove in each of said rollers, a member on said container extending into said groove for guiding the container, and mechanism for reciprocating said container on said rollers to create waves in the bath within the container.

3. In a photographic apparatus, the combination with a support, of a container movable relative to said support for containing a print treating bath, mechanism for moving said container relative to said support to create waves in the bath to flow over and submerge a print deposited therein, and guiding means stationary relative to said support for limiting movement of a print within the bath during the movements of the container.

4. In a photographic apparatus, the combination with a support, of a container for holding a print treating bath movable relative to said support, mechanism for moving said container to create waves in the bath for flowing over and submerging a print deposited therein, and a grid stationary relative to said support and placed partially within said bath for limiting the movement of a photographic print placed in the bath.

5. In a photographic apparatus, the combination with a frame, of print conveying mechanism, a movable container for holding a print treating bath, print guiding means comprising a grid-like structure mounted on said frame and having sides projecting downwardly into said container and a bottom extending across a portion of the container below the surface of the bath therein, means for removing a print from said conveying mechanism and depositing it in said bath within said grid-like structure, and mechanism for shifting said container to cause waves in the bath to flow over and submerge the print.

6. In a photographic apparatus, the combination with print conveying mechanism, of a movable container for holding a print treating bath, means for removing a print from said conveying mechanism and depositing it in said bath, a driving shaft, mechanism including a rock shaft for operating said print removing means, means including a gear on said driving shaft for oscillating said rock shaft for operating said print removing means, a crank member, means including another gear on said driving shaft for rotating said crank member, and a link connecting said crank member to said container for reciprocating said container to cause waves therein to flow over and submerge a print deposited in the bath.

7. In a photographic apparatus, the combination with a casing, of print conveying mechanism movable therein, a container within said casing for holding a print treating bath, means for removing a print from said conveying mechanism and depositing it in said bath, a shaft passing through said casing, an arm on said shaft exteriorly of said casing, another arm on said shaft in the interior of the casing, a rotatable driving member, mechanism including a link connected to said exterior arm of said shaft and driven by said driving member for oscillating the shaft, and a substantially U-shaped link interconnecting the interior arm on said shaft with said print removing means for driving the latter from the former.

8. In a photographic apparatus, the combination with a casing, of print conveying mechanism movable therein, a container movably mounted within said casing for holding a print treating bath, means for removing a print from said conveying mechanism and depositing it in said bath, a shaft passing through said casing, an arm on said shaft exteriorly of said casing, another arm on said shaft in the interior of the casing, a rotatable driving member, mechanism including a link connected to the exterior arm of said shaft and driven by said driving member for oscillating the shaft, a link interconnecting the interior arm of said shaft with said print removing means for driving the latter from

the former, a crank member separate from said shaft and rotated by said driving member, and a link operatively connecting said crank member to said container for reciprocating the container to create waves in said bath to flow over and submerge a print deposited therein.

9. In a photographic apparatus, the combination with a container for holding a print treating bath, of an inclined member partially within said container and extending downwardly to a point below the surface of said bath, said container and inclined member being movable relatively to each other, and mechanism for causing relative movement between said inclined member and said container so that said inclined member will act as a cam on the edge of a print in the bath and tend to move said edge downwardly.

10. In a photographic apparatus, the combination with a container for holding a print treating bath, of a grid-like structure partially within said container, said structure having a bottom below the surface of the bath within said container and inclined sides extending upwardly from said bottom, said container and grid-like structure being mounted for movement relative to each other, and mechanism for producing relative movement between said container and said grid-like structure so that said inclined sides will act as cams on the edges of a print in the bath within said structure and will tend to depress said edges of the print.
